(57) **CLAIM**

The ornamental design for a computer display panel with a graphical user interface for a mortgage application, as shown and described herein.

DESCRIPTION

The FIGURE is a front view of a computer display panel with a graphical user interface for a mortgage application, showing our new design.

The dot-dash broken line in the drawing illustrates portions of the computer display panel that form no part of the claimed design. The dashed broken lines illustrate portions of the graphical user interface and form no part of the claimed design.

1 Claim, 1 Drawing Sheet
